(57) CLAIM

The ornamental design for heel-less no-show socks, as shown and described.

DESCRIPTION

FIG. 1 is a top right perspective view of heel-less no-show socks showing my new design;

FIG. 2 is a top left perspective view thereof;

FIG. 3 is a bottom perspective view thereof;

FIG. 4 is a front elevated view thereof;

FIG. 5 is a rear elevated view thereof;

FIG. 6 is a top plan view thereof;

FIG. 7 is a bottom plan view thereof;

FIG. 8 is a left elevated view thereof; and,

FIG. 9 is a right elevated view thereof.

The broken lines showing of a foot in FIG. 1-9 are included for the purpose of showing environmental structure and form no part of the claimed design.
